HERBERT WATMOUGH PUDAN, OF CARMEL, CALIFORNIA

FLOTATION ORE CONCENTRATING MACHINE

Application filed February 23, 1924, Serial No. 694,782. Renewed February 10, 1931.

The invention relates to an improvement in flotation concentration machines. The object of my invention is to provide a flotation machine capable of doing the same work as accomplished by what is commonly called a calow cell. My machine is of more simple construction as it dispenses with the air basket or porous bottom through which the air is blown into the cell. My machine is pre-eminently adapted for the recovery of values from mill tailings because its operation entails no moving parts other than the pulp itself, it has no impellers, no air baskets, takes little operating head and only needs the occasional visits of an operator. There is little to wear out; the original cost of the installation is the whole expense.

For cleaning or raising the grade of the concentrates made by my machine or for the regular flotation work in a concentrating mill I modify the machine by providing it with additional air, generated by a suitable blower or air lift. This air is introduced and incorporated by the machine without the use of moving parts and without the necessity of air baskets or porous bottom.

The machine can be run continuously, there is nothing to replace, no need of any shut-down. All other flotation machines are at times shut down to replace motors, impellers or air blankets. Having found a method for doing away with mechanical agitation and air blankets my machine is very inexpensive to build. For its size it has great capacity; one cell as usually constructed handles 250 tones of dry pulp per 24 hours.

One important feature of my invention is the placing of these cells back to back and in rows parallel with each other thus giving a great treatment capacity in a limited area and with very little loss of operating head.

I will now proceed to describe the construction of my machine. In the following accompanying drawings:

Fig. 1 is a sectional elevation of my invention.

50 Fig. 2 is a plan view of the same.

Fig. 3 is a transverse section cut through the cells.

Fig. 4 is a sectional elevation showing the air lift arrangement.

55 Fig. 5 is a plan view of a general installation.

Fig. 6 is a cross-section of the same.

Referring to Fig. 1, the pulp to be treated enters the open feed box 1 through the pipe 2 which is immediately above the vertical downpipe 3 connecting into a horizontal header or feed box 4. The vertical feed pipe can be made several feet high and is designed to entrain air with the descending pulp. The horizontal feed box 4 is made air tight, excepting where the feed enters and leaves the box, and contains air and pulp under pressure due to the action of the falling column in the downpipe 3. Near the bottom of the feed box 4 and submerged 70 under the pulp are openings 5 leading from the feed box or header into the flotation or frothing cells 6. The air charged pulp enters the comparatively shallow flotation cells through these openings and immediately finds its velocity and pressure greatly reduced thus permitting the escape of the entrapped air and the formation of a froth carrying up a concentrate. The pulp is prevented from agitating the head end of the 75 cell by the baffle or grid 7. The flotation cell is wide at the bottom 8 and narrow at the top. Being wide at the bottom slows up the pulp and being narrow at the top gives the froth some velocity and helps to crowd it over the froth lips 9 and into the froth launder 10. A V shaped froth splitter is provided at the end of the cell. This

80 parts the froth and assists it to flow over the froth lips. An adjustable weir is provided at 11. By means of this adjustment the pulp level in each cell is regulated and the pulp is caused to flow from the feed box the whole length of the cell to the weir 85 where it drops into the tailings launder, 12. At the bottom of the cell below the weir are spigots 13. These are to prevent the accumulation of sand on the bottom of the cell. The bottom of the cell 8 is given a 90

95

100

slope towards the outlet tending of itself to prevent any accumulation of sands.

The cells can be arranged back to back and in parallel rows with a common header 4 and froth launders 10 in between the cells. In this manner great capacity is obtained in a small space and without any appreciable loss of head.

For general mill work and the retreatment of concentrates I find it advisable to provide air from a blower and pipe 14 to the machine. By maintaining a pressure or dynamic head of 1, 2, 3 or more pounds in the general feed box 4 I am able to introduce as much as is necessary of additional air under pressure into the feed box at any convenient intake such as 15. The additional air whirls around with the pulp in the feed box and becomes incorporated with and 20 completely saturates it. On entering the frothing cell 6 such a mixture is very effective.

Another method of accomplishing the same purpose is to use an air lift 16 as 25 illustrated by Fig. 4. This is particularly suitable where the pulp has to be raised to the flotation plant or raised from say the roughers to the cleaners.

The construction of the frothing cells and 30 air tight or pressure feed box is the same as before. In place of the down pipe 3 it becomes a stand pipe 17, the object of which is to maintain a head of 1, 2, 3 or more pounds on the feed box 4. In operation the 35 air lift 16 raises the pulp to the top of the stand pipe, but it does not overflow there, the outlet is the pressure outlet 5, leading into the frothing cell 6. The air lift connection to the feed box can be made at any 40 convenient point such as 18.

The operation of the machine or machines is very simple. Pulp enters the feed box 1, takes up air by flowing down the pipe 3, reaches the general feed box 4 under 45 pressure and there, if necessary, takes up additional blower or air lift air by means of the intake 15, passes through opening 5 into frothing or flotation cell 6 where it loses its velocity and pressure to such an extent that froth comes over the lips 9. This froth is collected in the froth launders 10 and run to a similar cleaning or enriching plant or to where desired. The pulp 50 now become tailings flows over the weir 11 and through spigots 13 to the tailings launder 12 or possibly to another series of cells.

The machine as used in conjunction with an air lift operates as follows:

60 Pulp flows into the air lift at any elevation depending on mill conditions and is raised or boosted up by the air lift to an elevation corresponding to near the top of the stand pipe 17. As the only outlet for the pulp is through the openings 5 the mix-

ture of pulp and air passes through these openings under considerable pressure and velocity into the frothing cells 6. The frothing cell operates the same as before.

I claim as follows:

1. A flotation concentrating machine comprising a pressure feed box, a standpipe opening from and extending above said feed box, an air lift extending below said box and adapted to deliver pulp at its top under pressure into said feed box, a froth separating cell communicating with and adapted to receive aerated pulp from the feed box. 70

2. A flotation concentrating machine of great treatment capacity consisting of a pressure feed box thru which the pulp to be treated is passed, air lifts, and standpipes connected to said pressure feed box, there being pulp discharge openings connected to a plurality of interconnected and adjoining 80 frothing cells disposed in a horizontal plane. 85

3. A flotation concentrating machine comprising a pressure feed box, a standpipe opening from and extending above said feed box, an air lift extending below said box and adapted to deliver pulp at its top under pressure into said feed box, the feed box being air tight otherwise than as to the 90 passage from the standpipe and the outlet to the froth separating cell and a froth separating cell communicating with and adapted to receive aerated pulp from the feed box. 95

4. A flotation concentrating machine of great treatment capacity consisting of a pressure feed box thru which the pulp to be treated is passed, air lifts, and stand pipes connected to said pressure feed box, said pressure feed box having pulp discharge openings, each of which connects with a froth separating cell, these cells adjoining each other in parallel lines with mutual froth collecting launders between and disposed in a horizontal plane. 100

In testimony whereof, I have hereunto 110 subscribed my name.

HERBERT WATMOUGH PUDAN.
